SPECIFICATION forming part of Design No. 18,684, dated October 9, 1888.

Application filed September 13, 1888. Serial No. 285,347. Term of patent 25 years.

To all whom it may concern:

Be it known that I, SIMON ZINN, a citizen of the United States, residing at New York, in the county and State of New York, have invented and produced a new and Original Design for Boxes, of which the following is a specification, reference being had to the accompanying photograph.

This invention relates to a box the body of which is formed to represent the head of Grover Cleveland.

The accompanying drawing shows a perspective view of my box.

In the drawing, the letter A designates the body of the box, which is formed to represent

the head of Grover Cleveland. B indicates the lid.

What I claim as new, and desire to secure by Letters Patent, is—

The design for a box herein shown and described, the same comprising the body A, formed to represent the head of Grover Cleveland, and the lid B, as set forth.

In testimony whereof I have hereunto set my hand and seal in the presence of two subscribers.
